UNITED STATES PATENT OFFICE.

FRANK A. CONRAD, OF ST. PAUL, MINNESOTA.

HOT-AIR FURNACE.

Application filed May 29, 1924. Serial No. 716,820.

My invention relates to hot air furnaces, and an object is to provide a furnace of this type in which the heat going to the various rooms is equally distributed, so that all of 5 the rooms in the building will receive their proper share of heat regardless of conditions tending to cause a greater flow of heated air to some of the rooms than to other rooms. Another object is to moisten and clean the 10 heated air supplied to the rooms. Another object is to conserve heat and prevent waste of fuel.

The full objects and advantages of my invention will appear in connection with the 15 detailed description, and the novel features embodied in my inventive idea will be particularly pointed out in the claims.

In the accompanying drawings which 20 illustrate the application of my invention in slightly different forms, Fig. 1 is a view of my furnace in vertical section. Fig. 2 is a view in horizontal section on the line 2—2 of Fig. 1. Fig. 3 is a view in horizontal section on the line 3—3 of Fig. 1. Fig. 4 is a 25 view in vertical section on the line 4—4 of Fig. 2. Fig. 5 is a view in horizontal section on the line 5—5 of Fig. 1. Fig. 6 is a view of a slight modification in horizontal section above the feed door. Fig. 7 is a view 30 corresponding to Fig. 4 and showing a modified form. Fig. 8 is a view in horizontal section of the form shown in Fig. 7. Fig. 9 is a view corresponding to Fig. 7 and showing a further modification.

Referring to the construction shown in the drawings and first, more particularly Figs. 1 to 5, the numeral 10 designates the firebox of a hot-air furnace having a casing 12 toward the lower end of which the firebox 10 and grate 14 are located, the ashpit 16 and its door 18 being below the grate. The casing 12 is provided as usual with a feed-door 20 and a smoke flue 22. Surrounding and spaced from the casing 12 is 45 a polygonal casing 24 having partitions 26 extending from its apices to the casing 12, whereby a plurality of chambers 28 are formed, these chambers being closed at their tops and open at their bottoms, as shown in Figs. 1 and 4. Surrounding and spaced from the casing 24 which may be termed an intermediate casing, is an outer casing or shell 30 provided at its upper end with a 50 fresh-air inlet pipe 32. Short pipe sections 34 extend outwardly from openings at the upper ends of the hot-air chambers 28. The

pipe sections 34 extend for a short distance through openings 36 in the casing 30 as best shown in Fig. 4, the pipe sections being smaller than the openings, so that an exit 60 from the space within the casing 24 is provided into the hot-air pipes 38. The pipe sections 34 also deliver air into the hot-air pipes 38, the capacity of the pipe sections 34 being preferably about double that of the 65 annular portions of the openings 36 which surround the pipe sections 34. The intermediate casing 24 stops short of the bottom of the furnace, and below the lower end of this casing is a water receptacle 40 which extends around annularly at the bottom of the furnace, except that it is interrupted at the place occupied by the ashpit door 18. The form of the invention shown in Fig. 6 is 70 similar to that already described, the difference being that the partitions 26 within the casings 24 are omitted, and, as shown, this casing is circular in cross-section instead of being polygonal. In the form of my invention illustrated in Figs. 7 and 8, the casings 12, 24, and 30 are rectangular in shape. Vertical partitions 26' extend between the casings 12 and 24. The hot-air pipes 38 extend from the top of the outer casing. Fresh air entering through the inlet pipe 32 75 passes around the pipe sections 34 and downwardly between the casings 30 and 24 and then upwardly between the casings 12 and 24, thereby becoming heated, and then passing out through the pipe sections 34. The form shown in Fig. 9 differs from that 80 shown in Figs. 7 and 8 on account of having the fresh air pipe 32' connected to the side of the casing or shell 30 instead of to the top.

The operation and advantages of my invention will be understood in connection with the foregoing description. Fresh air entering through the inlet pipe 32 passes 85 downwardly into the furnace between the outer casing 30 and the casing 24, and after coming into contact with the water in the receptacle 40 passes upwardly between the casing 24 and the inner casing 12. The air when it passes over the water, takes up moisture and is freed from impurities. From the space between the inner casing 12 and the casing 24, the heated and moistened air passes through the short pipe sections 34 into the hot air pipes 38 which supply hot air to the different rooms of the building. Under ordinary working conditions of the 90 furnace, the pipes 38 will receive all or the 95

greater portion of their supply of air through the pipe sections 34. However, if conditions arise so that one or more of the pipes 38 start to convey more than their proper amount of heated air, whereby the suction through such pipes is materially increased, then some of the fresh air coming in through the inlet pipe 32 will pass through the annular openings 36 around the pipe sections 34, thereby reducing the amount of heated air passing through the sections 34. The arrangement described, therefore, acts as an equalizer to keep the rooms heated by the furnace at a uniform temperature regardless of extraneous conditions, such as the direction of the wind. As will be apparent from Fig. 2, it will be understood that in one form of the invention, it is contemplated that there will be one of the chambers 28 and its associated pipe section 34 leading into a hot air supply pipe 38 for each room of the building which is to be heated by the furnace. The provision of the outer casing 30 spaced outside of the casings 24 causes a saving of fuel. This results from the fact that the fresh air passes down through the space between these two casings so that the outer casing is kept cool and very little heat is radiated into the basement or other place where the furnace is located.

The employment of my invention eliminates obstruction in the basement or cellar on account of the cold air intake being placed at the ceiling instead of at the floor, thereby saving space and conserving light, and the fresh air intake may also be somewhat smaller than usual. Inside or outside air is just as easily delivered to the plant, there being no difference in the construction or appearance of the intake pipe except that when inside air is taken an inside intake register must be attached to the pipe near the floor. My furnace has a cool outer shell at all times and under all conditions of operation. This is the case because the outer shell is in effect a continuation of the cold air intake itself. A cool outer shell tends to a saving of fuel and heat, besides keeping the basement cool. The admitted fresh air is divided before and not after it is heated or has come in contact with the heater core. This method assures the accurate distribution of the air after it is heated. There are no overheated conduit pipes. On account of the accurate division of the incoming air with respect to the heat generated within the apparatus all of the hot air supply pipes are at the same temperature which under normal conditions of firing would mean moderately warm. The conduit pipes need not be run at any particular pitch and neither need there be much concern that one pipe may be longer or of a longer run than some of the others. The conduit pipes may run on a level or may even form an inverted

U provided that a reasonable elevation of the final outlet is maintained above the plant itself. This is possible because of the "heat engine" character of the apparatus in that air is forced by the action of heat upon it to flow through and out of the apparatus by way of the channels provided therefor. As a consequence a more convenient placing of the apparatus in the basement is provided. Another feature is the standard size of the conduit pipes which carry heated air from the apparatus. These pipes do not need to be more than eight inches in diameter which in itself involves a saving of light and space overhead. I preferably provide an unusually high fire dome or core which insures more cubical content for combustion purposes, and also more surface for radiation purposes beside assuring a longer life to the core due to its greater ability to withstand high temperatures. When one or more of the hot air pipes are closed, the heat thus shut off from the closed pipes will be distributed to the remaining hot air pipes. The partitions 26 and 26' provide means for dividing the air before it is heated for distribution so that the cold air is forced against every square inch of the heated metal.

I claim:

1. In a hot air furnace, the combination of a plurality of hot air pipes leading therefrom, means for supplying cold air to the furnace to be heated thereby, and a plurality of short pipe sections smaller than said hot air pipes and corresponding in number thereto for conducting hot air supplied by the furnace into said pipes respectively, said pipe sections being so arranged that some of the cold air entering the furnace may pass outside of said sections directly into said pipes to equally distribute the amount of hot air delivered by all of said pipes for varying directions of the wind.

2. In a hot air furnace, the combination of a plurality of hot air pipes, an intermediate casing surrounding and spaced from the furnace casing, the lower end of said intermediate casing stopping short of the bottom of the furnace, an outer casing from which said hot air pipes lead, said outer casing surrounding and being spaced from said intermediate casing with its lower end extending to the bottom of the furnace, a fresh air pipe leading into the space between said intermediate and outer casings, and a plurality of short pipe sections smaller than said hot air pipes and corresponding in number thereto for conducting hot air from the space between said intermediate and the furnace casing into said pipes respectively, said pipe sections being so arranged that some of the cold air supplied by said fresh air pipe may pass outside of said sections directly into said pipes to equally distribute the amount of hot

air delivered by all of said pipes for varying directions of the wind.

3. In a hot air furnace, the combination of an intermediate casing surrounding and spaced from the furnace casing, the lower end of said intermediate casing stopping short of the bottom of the furnace, an outer casing surrounding and spaced from said intermediate casing with its lower end extending to the bottom of the furnace, a plurality of hot air pipes leading from the upper portion of said outer casing, a fresh air pipe leading into the upper portion of the space between said intermediate and outer

casings, and a plurality of short pipe sections extending from said intermediate casing into the inner ends of said hot air pipes respectively, said pipe sections being smaller than said hot air pipes whereby annular openings are provided through which some of the cold air supplied by said fresh air pipe may be delivered directly into said hot air pipes to equally distribute the amount of hot air delivered by all of said pipes for varying directions of the wind.

In testimony whereof I hereunto affix my signature.

FRANK A. CONRAD.
